(57) **CLAIM**

We claim the ornamental design for a remote electrical display module, as shown and described.

DESCRIPTION

FIG. 1 is a perspective view of a remote electrical display module according to the invention;

FIG. 2 is a rear view of the remote electrical display module of FIG. 1;

FIG. 3 is a front view of the remote electrical display module of FIG. 1;

FIG. 4 is a left side view of the remote electrical display module of FIG. 1;

FIG. 5 is a right side view of the remote electrical display module of FIG. 1;

FIG. 6 is a bottom view of the remote electrical display module of FIG. 1; and,

FIG. 7 is a top view of the remote electrical display module of FIG. 1.

The broken line showing of the environment is for illustrative purposes only and forms no part of the claimed design.
